US00D591132S

(12) **United States Design Patent**
Fischer-Zernin

(10) **Patent No.:** **US D591,132 S**
(45) **Date of Patent:** **** Apr. 28, 2009**

(54) **TACKER**

(75) Inventor: **Suzanne Fischer-Zernin**, Hamburg
(DE)

(73) Assignee: **Joh. Friedrich Behrens Ag**, Ahrensburg
(DE)

(**) Term: **14 Years**

(21) Appl. No.: **29/306,740**

(22) Filed: **Apr. 15, 2008**

(30) **Foreign Application Priority Data**

Nov. 5, 2007 (EM) 000821228

(51) **LOC (9) Cl.** **08-05**

(52) **U.S. Cl.** **D8/69**

(58) **Field of Classification Search** D8/68-69;
81/57.11, 429, 454, 455, 456, 469, 489; 173/13,
173/104, 114, 168, 169-171, 178, 201, 211,
173/213, 217; 408/20, 124, 125, 234, 241 R;
451/358; 310/50; 227/113, 114, 120, 130,
227/136, 142

See application file for complete search history.
